UNITED STATES PATENT OFFICE.

JOHN L. ALLEN, OF HASTINGS, MICHIGAN, ASSIGNOR TO CONSOLIDATED PRESS AND TOOL COMPANY, OF HASTINGS, MICHIGAN, A CORPORATION OF MICHIGAN.

NON-REPEATING CLUTCH FOR DIE-PRESSES.

No. 903,545.

Specification of Letters Patent.

Patented Nov. 3, 1903.

Application filed May 20, 1903. Serial No. 433,848.

To all whom it may concern:

Be it known that I, JOHN L. ALLEN, a citizen of the United States, residing at Hastings, in the county of Barry and State of Michigan, have invented new and useful Improvements in Non-Repeating Clutches for Die-Presses, of which the following is a specification, reference being had to the accompanying drawings, forming a part thereof.

10 The purpose of this invention is to provide an improved device of the nature of a clutch and operating means for the same for connecting the fly wheel of a press with the operating shaft thereof, which shall prevent the 15 press from performing more than one action,— that is, prevent the shaft from making more than one complete revolution after being tripped into engagement with the fly wheel without a repetition of the voluntary act of 20 the operator for tripping it into engagement.

It consists of the elements and features of construction shown and described as indicated in the claims.

In the drawings:—Figure 1 is a front elevation of a portion of a die press, comprising the operating shaft, fly wheel and clutch device thereon, embodying this invention. Fig. 2 is a section at the line 2—2 on Fig. 1 showing the parts in their normal position at rest. 25 Fig. 3 is an enlarged detail elevation of the parts shown in Fig. 2 pertaining to this invention, certain casings being partly broken away to disclose the parts within. Fig. 4 is a detail section at the line 4—4 on Fig. 3.

30 It may be understood that the drawings are intended to represent a die press of ordinary construction in the main features, a particular form of the device for engagement of the fly wheel with the shaft and for tripping the same being necessarily adopted in order 35 to illustrate the application of this invention. The portion of the press standard or form is shown at A in which is journaled the press crank shaft, B, having the enlargement, B¹, 40 and on which the fly wheel, C, is mounted loose for rotation, a dog, D, being provided for engaging the shaft and wheel to operate the press. It will be understood that the 45 dog is mounted for sliding relatively to the shaft to become engaged with and disengaged 50 from the fly wheel, being normally shot into

engagement by the spring, not shown, and being forced out of engagement by the tripping cam, F. This tripping cam is pivoted on the bracket, G, mounted upon the press 55 standard, and is provided with a spring-operated plunger, H, for holding it at the free end normally up into the path of the abutment, D¹, on the dog, D, so that the rotation of the shaft causes the abutment to run on to the 60 tapering end of the tripping cam for wedging the dog out of engagement with the fly wheel to bring the press to rest. It will be understood that in the usual or ordinary construction of such presses, the tripping cam is connected by a rod to the pedal by which it is 65 pulled down out of its position for stopping the abutment, and that by this action the dog is released and allowed to be shot into engagement with the fly wheel which communicates 70 rotation to the shaft and maintains it as long as the tripping cam is thus held down out of the path of the abutment, the engagement of the fly wheel and shaft being effected and the shaft being brought to rest only 75 when the operator releases the pedal and allows the tripping cam to be thrust back by the spring-pressed plunger, H, into the path of the abutment, D¹.

The present invention consists of the features now to be described associated with the tripping cam for permitting it to be forced back into tripping position after the wheel completes one revolution, without release of the pedal. For this purpose, the 80 tripping cam, F, is connected with the pull-rod, K, (which may be understood as extending to a pedal, not shown,) by means of a two-part link whose members, M and N, telescope with each other, the upper member 85 M, being connected by a short link, L, with the tripping cam, (such short link being provided merely to accommodate the movement of the tripping cam about its fulcrum to the sliding movement of the telescoping 90 link,) and the lower member, N, of the two-part link being connected with the pull-rod, K. The two members, M and N, of the telescoping link are engaged with each other by a dog, P, lodged in a transversely projecting 95 seat, N¹, provided on the lower link member, and thrust into engagement with the notch, 100

M¹, in the link member, M, by means of a spring, O. The dog, P, has a projection, p, which is engaged by a trigger, S, fulcrumed on the bracket, G, and extending up between said abutment, p, and the slide bearing of the two telescoping link members upon each other, the upper end of said trigger being in the path of an abutment, B², on the enlargement, B¹, of the shaft, situated thereon at such point as to encounter the trigger a little before the point at which the disengagement of the fly wheel and shaft should occur for bringing the press to rest.

When the operator by depressing the pedal (not shown) causes the two-part telescoping link whose two parts are locked together by the dog, P, to pull down the tripping cam, the dog, D, engages the fly wheel and shaft in the usual manner and the shaft is rotated, but before the shaft has made one complete revolution, its abutment, B², encountering the trigger, S, causes the latter to pull out the dog, P, and disengage the two telescoping link members from each other, leaving the upper member, M, free to be pulled upward by the tripping cam which is forced upward by its spring-pressed plunger, and the tripping cam being thus returned to tripping position wedges the dog, D, out of engagement with the fly wheel, causing the press to come to rest, notwithstanding the operator may be still holding the pedal depressed and thereby keeping the lower link member, N, withdrawn. In order to cause the press to make another stroke, the operator must release the pedal to let the link member, N, return upward, and in order that it may be thus returned, notwithstanding it is disconnected from the cam, there is provided a spring-pressed plunger, T, operating upon the projecting seat, N¹, of said lower link member for thrusting it upward. As soon as the lower link member is thus returned upward to bring the notch, M¹, into line with the dog, P, the latter enters the notch and the two link members are again engaged, and the down-pull of the pull-rod when the pedal is next depressed will withdraw the two-part link and the tripping cam connected therewith downward for permitting the engagement of the fly wheel and shaft by the dog, D.

In order that the trigger, S, may not in any case interfere with reversing the shaft, as is sometimes necessary in manipulating the press, said trigger is not positively connected with the dog, P, which it is designed to operate, but is only arranged to operate it by encounter with the abutment, p, at one side thereof, being free to swing away from the abutment without operating the dog or being restrained by it; and a spring, V, is provided on the trigger to hold it yieldingly

against the abutment, p, of the dog in order to position the trigger definitely as if the two parts were positively connected.

I claim:—

1. In combination with a press shaft and fly wheel, a dog for engaging them; a spring-pressed cam for withdrawing the dog; a two-part link of which one link member is connected with the cam; pulling means connected with the other link member; a dog mounted on one of the link members for engaging the other to lock them together; a trigger for withdrawing said dog and an abutment revolving with the shaft for encountering the trigger to withdraw the dog. 70

2. In combination with a press shaft and fly wheel, a dog for engaging them; a spring-pressed tripping cam for withdrawing the dog; a two-part link whose members telescope with each other, one link member being connected with the tripping cam; a pull-rod connected with the other link member; a dog mounted on the first-mentioned link member, the second link member having a notch for engagement with the spring-pressed dog to lock the two members against relative extension; a trigger for withdrawing the dog and an abutment revolving with the press shaft for encountering the trigger, and a spring operating on the lower link member for yieldingly resisting the down pull of said member and returning it upward. 95

3. In combination with a press shaft and fly wheel and the dog for engaging them, a spring-pressed cam for withdrawing the dog; a two-part link of which one link member is connected with the cam; pulling means connected with the other link member, and means by which the two members are disengageably engaged for transmission of the pull on the latter member to the former, said link members being telescoped with each other. 100

4. In combination with a press shaft, fly wheel and dog for engaging them; a spring-pressed cam for withdrawing the dog; a two-part link of which one member is connected with the cam; operating means connected with the other link member; a dog mounted on one of the link members for engaging the other to lock them together; a trigger engaging the dog only in one direction for withdrawing it; a spring which resists the movement of the trigger in the opposite direction, and an abutment revolving with the shaft for encountering the trigger to withdraw the dog. 115

5. In combination with a press shaft and fly-wheel, and the dog for engaging them, a spring-pressed cam for withdrawing the dog; a two-part link of which one link member is connected with the cam; pulling means connected with the other link member, said 125

members being telescoped with each other, the inner member being notched for engagement; a dog carried by the outer member for such engagement, and means operated by 5 the rotation of the shaft for disengaging the dog.

In testimony whereof, I have hereunto set

my hand, in the presence of two witnesses, at Hastings, Mich., this 12th day of May, 1908.

JOHN L. ALLEN.

In the presence of—

GEO. E. COLEMAN,

ARTHUR A. CROTHERS.
